UNITED STATES PATENT OFFICE.

LOUIS OTT, OF HARRISBURG, PENNSYLVANIA.

GAS-LIGHTER.

1,099,511.

Specification of Letters Patent.

Patented June 9, 1914.

Application filed January 28, 1913. Serial No. 744,747.

To all whom it may concern:

Be it known that I, Louis Ott, a citizen of the United States, residing at Harrisburg, in the county of Dauphin and State 5 of Pennsylvania, have invented certain new and useful Improvements in Gas-Lighters, of which the following is a specification, reference being had to accompanying drawings.

10 This invention relates to gas lighters and more particularly to a pilot light designed to be used in connection with gas stoves or ranges.

15 The principal object of the invention is the provision of a gas lighter comprising a pilot light adapted to burn continuously, the flame thereof being adapted to be increased in size when the pilot tube is moved into close proximity to the stove burners.

20 Another object of the invention is the provision of a housing suitably supported upon the stove frame between the burners thereof and provided with a rotary plug which has secured to the upper end thereof

25 a pilot tube, means for admitting gas to the pilot tube through the rotary plug and means for admitting additional gas thereto to increase the size of the pilot light when the latter is moved into close proximity to 30 the gas burners.

Another object of the invention is the provision of a gas lighter of the above stated character which is provided with means for regulating the size of the pilot 35 light.

A still further object of the invention is the provision of a gas lighter of the above stated character provided with means for controlling the gas supply to increase the 40 size of the light.

A still further object of the invention is the provision of a gas lighter provided with a rotary pilot tube and hand operable means connected to the pilot tube whereby the latter may be moved into close proximity to the gas burners.

A still further object of the invention is the provision of a gas lighter of the above stated character including a pilot tube, the 50 end of which is provided with a shield arranged below the orifice in the end thereof adapted to prevent the pilot light from being puffed out upon the lighting of the gas burners of the stove.

55 With these and other objects in view as

will appear as the description proceeds, the invention comprises the various novel features of construction, combination and arrangement of parts as will be more fully described hereinafter and set forth with 60 particularity in the appended claims.

Referring to the drawings, Figure 1 represents a top plan view of a gas stove with my improved gas lighter attached thereto; Fig. 2 is a section taken on the line 2—2 65 of Fig. 1. Fig. 3 is a vertical longitudinal sectional view through the rotary valve and the housing therefor; Fig. 4 is a horizontal section taken on the line 4—4 of Fig. 3; Fig. 5 is a vertical transverse section taken 70 on the line 5—5 of Fig. 3; Fig. 6 is a vertical section taken on the end of the pilot tube and the shield secured thereto.

Similar characters of reference are used to denote like parts throughout the accompanying drawings and the annexed specification. 75

Referring more particularly to the drawings the reference character 1 indicates a gas stove which may be of any desired shape 80 or design and is provided with the usual burners 2 which are disposed below the top plate 3 and are separately connected by means of gas pipes 4 to the main gas supply pipe 5 disposed at one side of the stove. 85

My improved gas lighter is shown to consist of a housing 6 which is mounted upon a supporting bar 7 and is securely held thereon through the medium of bolts 8. This bar, in this instance, is shown as arranged 90 transversely of the stove, and is supported by rods 9 that extend longitudinally of the stove and are suitably secured to the opposite ends thereof. The bar 7 is secured to the supporting rods 9 through the medium 95 of angularly shaped clamps 10 which are securely clamped over the supporting rods 9 and to the bar 7 by bolts 11. The housing 6 is provided at one end thereof with a vertically extending tapered bore 12 in 100 which is revolvably mounted a tapered plug 13, securely held therein for free rotation through the medium of washers 14 and a screw 15 threaded to the lower end of the plug 13. The upper end of the 105 tapered plug 13 is provided with a crown gear 16 that meshes with a pinion 17 secured to the inner end of an operating shaft 18, the forward end of which is journaled in a suitable supporting bracket 19 110

2

formed upon the base flange of the housing 6, and the other end is journalized in a bracket 20 formed at the end of the bar 7. The outer end of the operating shaft 18 is provided with a suitable hand wheel 21 whereby the plug 13 may be revolved through the medium of the crown gear 16 and the pinion 17 connected thereto and to the operating shaft 18. The upper end of the plug 13 is formed to provide a horizontally extending arm 22 which is threaded at the end to receive the threaded end of a pilot tube 23, the outer end of which, as shown in Fig. 6, is provided with a reduced orifice 24 where a pilot light of the desired size is adapted to burn continuously.

A shield 25 is secured to the lower portion of the pilot tube 23 beneath the orifice 24 so as to prevent the pilot light from being puffed out upon the lighting of the gas stove burners. When the pilot tube rests in its normal position the pilot light burns above the shield 25, but when the pilot tube is moved into close proximity to the gas stove burners the pilot light is automatically increased in size so as to project forwardly beyond the end of the shield 25 so as to readily and quickly light the burners. The pilot light will decrease to its normal size when the pilot tube has again moved to its normal or inoperative position.

The tapered plug 13 is provided centrally with an orifice 26 opening through the upper end of the plug and is closed by a screw plug 27. The lower end of the orifice 26 communicates with an annular groove 28 formed in the outer face of the plug 13 through the medium of a horizontally extending passage way 29. The plug 13 has a pair of vertical semi-annular grooves 30 formed therein arranged below and in spaced relation to the annular groove 28. These grooves 30 are connected to the annular groove 28 by vertically extending inclined grooves 31. The arm 22 of the plug 13 is provided with a horizontally extending passage way 32 which communicates with the central orifice 26, thus establishing communication between the pilot tube 23 and the annular groove 28.

The housing 6 is provided at the upper portion thereof with a horizontally extending extension 33 which has formed therein a horizontally extending passage way 34, the passage way at one end communicating with the tapered bore 12 and the annular groove 28 of the plug 13, the other end of the passage way being closed by a screw plug 35. The extension 33 is provided below and in spaced relation to the passage way 34 with a secondary passage way 36 which is enlarged and internally threaded, as shown at 37, at the outer end thereof for the reception of the gas supply pipe 38. The other

end of the passage way 36 communicates 65 with the bore 12 of the housing 6 and with the partial semi-annular grooves 30 of the plug 13 when the latter is rotated to an operative position. The passage way 36 is provided intermediate its ends with a transversely extending controlling valve 39 which is shown to be in the form of a tapered plug provided with a transverse opening 40 whereby the gas may be allowed to pass through the passage way 36 into the grooves 75 30. This controlling valve 39 is designed to regulate the admission of gas to the grooves 30, whereby the increased size of the pilot light may be varied at will. The extension 33 is also provided with a vertically extending opening 41 which extends from the top of the extension 33 down through the passage way 34 where it is reduced in size to form a valve seat 42 and a passage way 43 establishing communication between the passage way 85 34 and the passage way 36. A plug 44 having the lower end thereof tapered is threaded into the opening 41 and adapted to be screwed down so that the lower end thereof may be disposed relative to the seat 42 to 90 regulate the passage of the gas from the inlet pipe 38 through the passage way 34 to the annular groove 28. In other words the plug 44 serves as a means for increasing or decreasing the size of the pilot light. 95

In the operation of the device, the parts being arranged in the position shown in Fig. 3, the pilot light burns at the orifice 24 continuously. When it is desired to light the various burners of the gas stove the operating handle or wheel 21 is revolved to impart a similar motion to the pilot tube 23, and in so doing the partial semi-annular grooves 30 are moved into communication with the passage way 36 whereby an additional supply of gas will be admitted to the annular groove 28, thus increasing the size of the pilot light so that the latter extends forwardly and beyond the end of the shield 25 whereby the gas burners may be readily and quickly lighted. After the burners have been lighted the pilot tube is again moved to its normal or inoperative position, the partial semi-annular grooves 30 being moved 105 out of engagement with the passage way 36 110 at the same time whereby the supply of gas to the pilot tube will be diminished so as to cause the pilot light to decrease to its normal size. 115

From the foregoing description taken in 120 connection with the accompanying drawings, the advantages of construction and the method of operation will be readily apparent to those skilled in the art to which the invention relates, and while I have described 125 the principle of operation of the invention, together with the device which I now consider to be the best embodiment thereof, I

desire to have it understood that such changes may be made when desired as are within the scope of the appended claims.

Having fully described the invention, what

5 I claim as new is:

1. The combination with a gas stove, of a gas lighter comprising a housing, a plug revolvably mounted in the housing and provided

10 with an orifice, a pilot tube carried by the plug and communicating with the orifice formed therein, means for supplying gas to the orifice in the plug for the pilot light, additional means for supplying gas to the plug when the latter is revolved to increase the 15 size of the pilot light and means for revolving the plug.

2. A gas lighter comprising a housing, a plug having a central orifice and a laterally extending passage, a pilot tube secured to 20 the upper end of the plug and projecting therefrom, said pilot tube communicating with the central orifice of the plug, said plug being formed in its outer face with an annular groove connected to the central orifice by the laterally extending passage way, said plug being also provided adjacent the annular groove with a partial annular groove, a groove connecting the annular groove and partial annular groove, means for supplying 25 30 gas to the annular groove, means for supplying gas to the partial annular groove, for the purpose set forth and means for revolving the plug.

3. A gas lighter comprising a housing 35 provided with a tapered bore, a plug revolvably mounted in said bore and provided in its outer face with an annular groove and centrally with a longitudinally extending orifice, said orifice and groove being connected 40 by a laterally extending passage way, the plug being further provided below the annular groove with a pair of partial annular grooves, grooves connecting the partial annular grooves to the annular groove, a valve 45 controlled passage way in the housing communicating with the annular groove of the plug, means for supplying gas to the partial annular grooves, and means for revolving the plug, for the purpose set forth.

50 4. A gas lighter comprising a housing

provided with a tapered bore, a plug revolvably mounted therein and provided in its outer face with an annular groove and centrally with a vertically extending orifice, said orifice and groove being connected by a 55 laterally extending passage way, a pair of partial semi-annular grooves disposed below the annular groove, grooves connecting the partial annular grooves to said annular groove, a valve controlled passage way in the 60 housing communicating with the annular groove, a valve controlled passage way disposed below the first named passage way and adapted to communicate with one of the partial semi-annular grooves, and means for 65 revolving the plug, for the purpose set forth.

5. A gas lighter comprising a housing provided with a rotary valve, a pilot tube secured to the valve and communicating therewith, a gear carried by said valve, a 70 pinion meshing with said gear, an operating shaft connected to the pinions, an operating handle for the shaft, means for supplying gas to the valve for the pilot light, and means for supplying additional gas to the 75 valve upon the rotation thereof to increase the size of the pilot light.

6. A gas lighter comprising a housing, a rotary valve mounted in said housing, means for revolving said valve, a pilot tube secured 80 to the valve and communicating therewith, a shield carried by the end of the pilot tube, valve controlled means for supplying gas to the valve for the pilot light, and valve controlled means for supplying additional gas 85 to the valve when the latter is rotated to increase the size of the pilot light.

7. A gas lighter of the class described comprising a rotary valve, a pilot tube secured to the valve, said tube being cut away 90 at the outer end to form a shield disposed below the orifice in the tube, and means for rotating the valve.

In testimony whereof I hereunto affix my signature in the presence of two witnesses. 95
